UNITED STATES PATENT OFFICE.

WALTER FERRIS, OF MILWAUKEE, AND SVANTE R. W. M. BAGER AND MITCHEL L. FYKSE, OF SOUTH MILWAUKEE, WISCONSIN, ASSIGNEES TO BUCKEUS COMPANY, OF SOUTH MILWAUKEE, WISCONSIN, A CORPORATION OF WISCONSIN.

COAL-LOADING SHOVEL.

1,289,426.

Specification of Letters Patent. Patented Dec. 31, 1918.

Application filed April 28, 1917. Serial No. 165,215.

To all whom it may concern:

Be it known that we, WALTER FERRIS and SVANTE R. W. M. BAGER and MITCHEL L. FYKSE, being citizens of the United States, 5 and the first a resident of Milwaukee and the others residents of South Milwaukee, in the county of Milwaukee and State of Wisconsin, have invented a certain new and useful Improvement in Coal-Loading Shovels, 10 of which the following is a specification.

Our invention relates to improvements in coal loading shovels and has for one object to provide a new and improved form of shovel, similar in some features to the ordinary type of steam shovel, which may be used in loading coal and other loose and friable material or which may be used in stripping off thin layers of dirt, soil and the like.

20 One object of our invention is to provide such a coal loading shovel as will be simple, easy and convenient in manufacture and operation. Another object is to provide a shovel which may be adapted from the ordinary type of dipper shovel or bucket without changing many of the essential parts. Another object is to provide a new and improved form of excavating machine. Other objects will appear from time to time in the 25 specification.

Our invention is illustrated more or less diagrammatically in the accompanying drawings, wherein—

Figure 1 is a side elevation;

35 Fig. 2 is a side elevation of the boom and associated parts;

Fig. 3 is a plan view of the end of the boom and shovel;

40 Fig. 4 is a side elevation of the boom showing certain modifications.

Like parts are indicated by like letters throughout the several figures.

A is a supporting truck. We have shown it here of the caterpillar type, though it 45 might obviously be of any suitable type. It carries a turn table A¹. Upon this turn table is rotatably mounted a platform A²; projecting upwardly from the platform is the ordinary mast A³ and resting upon the platform are the ordinary operating and driving winches, engines and the like A⁴. A⁵

is a sheave mounted at the upper end of the mast A³. A⁶ is the ordinary type of excavator boom pivoted on the platform A² and reinforced by the triangular frame work A⁷ at the apex of which is a sheave A⁸. A⁹ is a hoisting cable anchored at the apex of the frame A⁷ and passing over the sheave A⁸ and A⁶ thence down to a part of the hoisting mechanism so that by proper manipulation by the operator the boom may be raised and lowered about its horizontal axis on the platform A².

B is a thrusting engine mounted on the boom A⁶. B¹ is a steam pipe whereby the steam is supplied to the engine from the boiler on the platform A². Suitable engine control means are provided not here specifically indicated. B² is a shipper shaft rotatably mounted on the boom A⁶ driven by means of a train of gears B³ from the engine B. This shipper shaft B² extends out beyond both sides of the boom and carries at its end the gears B⁴. B⁵, B⁶ are racks in mesh with the gears B⁴. These racks are mounted upon the two-part dipper handle. This dipper handle is made up of the side members B⁷ located one on either side of the boom together with a cross plate B⁸ extending across between the side members 50 beneath the boom and a tie yoke B⁹ which also extends across beneath the boom. B¹⁰, B¹¹ are rollers mounted on the forward end of the dipper handle and adapted to ride in the channels outwardly open forming the 55 sides of the boom. The rear end of the dipper handle is supported from the shipper shaft by means of stirrups B¹² which extend down on either side of the gears B⁴ and hold the members in such position that the racks 60 are always in mesh with the gears.

Extending downwardly from the dipper handle is a frame member made up of the two short supporting arms C perpendicular to the handle and the inclined thrust or 65 strut members C¹ extending rearwardly from the end of the members C to the dipper handle adjacent the rearmost end. These strut members are stiffened by a cross piece C² and held against bending by the 70 members C³. A plate C⁴ interposed between the plate B⁸ and the pieces C, C¹, adds to

the stiffness and rigidity of the structures and strengthens the part at the point where the bucket is to be attached. C⁵ is a dipper or bucket pivoted at the lower end of the 5 member C free to rotate with respect thereto. The dipper is so arranged that when empty its center of gravity comes behind the pivot point, when loaded its center of gravity comes in front. It is provided with 10 the usual type of forwardly extending cutting teeth C⁶ and is adapted to be locked against rotational movement when in the excavating position by means of the lock bolt C⁷ engaging a member C⁸ on the back of the 15 bucket and thrust into the locking position by the spring C⁹. C¹⁰ is a pivot engaging chain extending to a lever C¹¹ which lever is adapted to be rotated by the operator who may pull on the cord C¹² to release the 20 latch and permit the bucket to dump.

In the modified form shown in Fig. 4 the boom D carries the thrusting engine D¹ which drives the gears D² in mesh with racks D³ on the bucket handle D⁴. The shipper 25 shaft carrying these gears, however, is mounted in a bracket D⁵ extending downwardly from the boom D and the rear end of the dipper handle is held in such position that the gears are held in mesh with 30 the rack by a roller D⁶ also on the bracket D⁵. Arms D⁷ extending upwardly from the forward end of the dipper handle carry rollers D⁸ which ride along the boom D and the bucket is attached to the forward end 35 of the bucket handle in the same way being pivoted in exactly the same manner as is the bucket in the preferred form, the only difference being that in this case, the dipper or bucket handle is immediately behind the 40 bucket and located below the boom instead of being along side of the boom and above the bucket as in the preferred form.

It will be evident that while we have shown in our drawings an operative device, 45 still many changes might be made in size, shape and arrangement of parts without departing materially from the spirit of our invention, and we wish therefore that our drawings be regarded as in a sense diagrammatic.

The use and operation of our invention are as follows:

The excavating machine is manipulated for moving it about from place to place, and 55 for rotating the turn-table about its pivot in the usual manner common to all excavating machines of the revolving type. The boom, however, is pivoted on the platform and is adapted to rotate about a horizontal axis. 60 Means are provided whereby the hoisting mechanism on the platform operates to raise and lower the boom.

The dipper handle, it will be noted, is held parallel with the boom, but is free to

move back and forth therealong when the 65 thrusting motor is worked. This dipper handle carries at its forward end the dipper and when the thrusting engine is operated to move the handle forward, the dipper will be thrust forward into the work. Under 70 ordinary circumstances, for excavating, the machine will assume the position shown in Fig. 1. The operator will then operate the thrusting motor and force the bucket forward into the work until the bucket is full. 75 When the bucket is full the thrusting motor will be stopped and the boom will then be rotated about its axis to lift the bucket away from the work. As soon as the bucket is lifted, the turn-table will be operated to 80 swing the bucket into the dumping position, when the latch will be released, the bucket will tip to dump its contents and as soon as the contents are dumped the force of gravity will close the bucket, the operator being 85 then ready to return the bucket to its position, taking first precaution, of course, to withdraw the bucket by moving the thrusting motor in the opposite direction so that the work can be repeated. 90

The two forms are exactly the same as far as the operation is concerned except that for some purposes it may be desirable to have the bucket handle located beneath the boom, though in either event the operation 95 is exactly the same and the general arrangement of the parts is, of course, as evident.

We claim:

1. An excavating machine comprising a boom having guide members upon its opposed sides and means for rotating it about a horizontal axis, a motor on the boom, a shipper shaft driven by the motor, a dipper handle pinion on the shipper shaft, a rack on the handle in mesh with the pinion and a stirrup mounted on the shipper shaft in 100 slideable engagement with the handle, guide members on the forward end of the handle riding in the guide members on the boom and a dipper pivoted on the handle. 105

2. An excavating machine comprising a boom having on either side flanged members, means for rotating it about a horizontal axis, a motor mounted upon it, a dipper handle having members on its forward end adapted 110 to engage the flanges, a rack on the handle, a shipper shaft on the boom having a pinion in mesh with the rack, a driving connection between the shaft and the motor and a stirrup pivoted on the shaft and in slideable engagement with the handle, a frame-work 115 downwardly depending from the handle and a bucket pivoted thereupon. 120

3. An excavating machine comprising a boom made up of channel members, means for rotating it about a horizontal axis, a motor mounted thereupon, a dipper handle adapted at its forward end to engage the 125

channel members, a rack on the handle, a
shipper shaft on the boom having a pinion
in mesh with the rack, a driving connection
between the shaft and the motor and a stir-
rup pivoted on the shaft and in slidale en-
gagement with the handle, a frame-work
downwardly depending from the handle and
a bucket pivoted thereupon.

Signed at South Milwaukee, Wisconsin,
this 21st day of March, 1917.
